CLAIM

The ornamental design for a cryogenic cooling system as shown and described.

DESCRIPTION

FIG. 1 is a front perspective view of a first embodiment of a cryogenic cooling system according to our new and ornamental design;

FIG. 2 is a front elevation view of the first embodiment of the cryogenic cooling system;

FIG. 3 is a rear elevation view of the first embodiment of the cryogenic cooling system;

FIG. 4 is a left side elevation view of the first embodiment of the cryogenic cooling system;

FIG. 5 is a right side elevation view of the first embodiment of the cryogenic cooling system;

FIG. 6 is a top plan view of the first embodiment of the cryogenic cooling system;

FIG. 7 is a bottom plan view of the first embodiment of the cryogenic cooling system; and

FIG. 8 is a front elevation view of the first embodiment of the cryogenic cooling system in an alternate configuration.

FIG. 9 is a front perspective view of a second embodiment of a cryogenic cooling system according to our new and ornamental design;

FIG. 10 is a front elevation view of the second embodiment of the cryogenic cooling system;

FIG. 11 is a rear elevation view of the second embodiment of the cryogenic cooling system;

(Continued)

FIG. 12 is a left side elevation view of the second embodiment of the cryogenic cooling system;
 FIG. 13 is a right side elevation view of the second embodiment of the cryogenic cooling system;
 FIG. 14 is a top plan view of the second embodiment of the cryogenic cooling system;
 FIG. 15 is a bottom plan view of the second embodiment of the cryogenic cooling system; and
 FIG. 16 is a rear elevation view of the second embodiment of the cryogenic cooling system in an alternate configuration.
 FIG. 17 is a front perspective view of a third embodiment of a cryogenic cooling system according to our new and ornamental design;
 FIG. 18 is a front elevation view of the third embodiment of the cryogenic cooling system;
 FIG. 19 is a rear elevation view of the third embodiment of the cryogenic cooling system;
 FIG. 20 is a left side elevation view of the third embodiment of the cryogenic cooling system;
 FIG. 21 is a right side elevation view of the third embodiment of the cryogenic cooling system;
 FIG. 22 is a top plan view of the third embodiment of the cryogenic cooling system;
 FIG. 23 is a bottom plan view of the third embodiment of the cryogenic cooling system;
 FIG. 24 is a front elevation view of the third embodiment of the cryogenic cooling system in a first alternate configuration; and,
 FIG. 25 is a rear elevation view of the third embodiment of the cryogenic cooling system in a second alternate configuration.
 The broken lines illustrate portions of the cryogenic cooling system that form no part of the claimed design.
